J. E. FERGUSON ET AL

DISPLAY CARTON

Filed Sept. 8, 1924

UNITED STATES PATENT OFFICE.

JAMES E. FERGUSON, OF CLEVELAND, AND HENRY L. MOONEY, OF EAST CLEVELAND, OHIO; ASSIGNORS TO THE LAKE LITHOGRAPH COMPANY, OF CLEVELAND, OHIO, A CORPORATION OF OHIO.

DISPLAY CARTON.

Application filed September 8, 1924. Serial No 736,490.

This invention relates to a display carton, more particularly it comprises a carton adapted to serve as a container and shipping package; also as a device for advertising 5 and displaying small articles of merchandise.

The object of the invention is to improve display cartons by making the same more simple in design and inexpensive to manufacture and at the same time to make them 10 more effective when used for advertising purposes.

The annexed drawing and the following description set forth in detail certain structures embodying the invention, such disclosed 15 means constituting, however, but one of various structural forms in which the principle of the invention may be used.

In said annexed drawing:—

Fig. 1 is a perspective view of the carton 20 embodying the invention with the cover therefor folded back into display position; Fig. 2 is a longitudinal sectional view taken along the line 2—2 shown in Fig. 3; Fig. 3 is a transverse sectional view taken along the 25 line 3—3 shown in Fig. 2; Fig. 4 is a perspective view on a reduced scale showing the carton in closed position; Fig. 5 is a plan view showing the blank from which the base section of the carton is formed, the corners at 30 which folds are made being shown in dotted lines; and Fig. 6 is a plan view of the blank from which the top section of the carton is formed, the corners at which folds are made being shown in dotted lines.

As is clearly shown in the drawing, the carton comprises a base section 1 and a top section 2 adapted to be assembled therewith to form the complete carton. The base section as is shown in Fig. 5 comprises the bottom 35 proper 3 which is of rectangular form and has integral side members 4 and end members 5 formed at the margins thereof. Said side and end members are designed to be folded up from the bottom but they need not be fastened at the corners for reasons which will presently appear. The top member as is clearly shown in Fig. 6 is formed from a single piece of sheet material and is provided with a tab 6 adjacent the lower edge 40 by means of which it may be folded into an open rectangular structure and is designed to be of a size to snugly fit over the base section when the side and end members thereof are turned up into box like shape. The top member thus serves as the means for assembling 45

in finished form the two members comprising the carton.

As will be noted more particularly in Fig. 6, the lower edge of the blank forming the member 2 is of a height corresponding with 60 the height of the side and end pieces of the base member 1. Adjacent the top extension 6 heretofore referred to, the cover portion 7 of the carton is formed, said cover being scored at four points transversely, the scoring near 65 its free end being designed to provide a tongue section 8 whereby the cover may be fastened in either closed or display position. The scoring adjacent the intermediate portion of the cover extends only partially across 70 the same, the central portion of said cover having a cut 9 of V shape or any other desired form to provide an ornamental edge when the cover is folded to display position as is shown in Fig. 1. The scoring adjacent 75 the base of the cover is designed to provide a short section 11 between the hinge of the cover and the adjacent larger section thereof which will serve to offset the two larger sections of the cover in inclined relation to 80 each other when the cover is folded into display position. The projecting angle thus formed is disposed so as to engage the rear end of the box and thus will prevent the cover from being folded back so far as to drop 85 advertising matter on the forward face thereof below the normal line of vision. Upon each of the longer sections of the blank forming the top member, which constitute the 90 sides of the carton, there is provided a lateral extension 12 adapted to be folded inwardly so as to occupy an angular position within the carton. Each of said extensions is scored along a line parallel to the free edge thereof so as to form a narrow strip 13 which may be 95 turned inwardly so as to rest against the bottom of the carton when the extensions are folded in inclined position therein. The extensions are preferably provided with cut out seats to receive the ends of various articles 100 of merchandise to be displayed in the carton. These seats may be appropriately shaped for the particular article to be displayed and in the form of construction illustrated, one of the extensions is shown with circular apertures 14 to receive the head portions of collapsible tubes containing rubber cement and the opposite extensions are provided with elongated oval shaped apertures to receive 105 the base portions of the collapsible tubes. 110

It is obvious that seats of different shape may be devised to conform to the particular shape of the articles to be placed in the carton.

From what has been described, it will be understood that the carton may be rapidly assembled from two blanks of the form shown in Figs. 5 and 6, each of said blanks being folded along the dotted lines and the tab 6 being secured by means of glue or other suitable fastening devices to the opposite end of the lower section of said blank. The entire carton is then ready for use and the articles of merchandise may be placed therein and the cover folded down over the goods with the tongue inserted between the two sections of card board at the end opposite to that to which the cover is hinged. The carton may then be stored or shipped until it is needed for sales purposes when the tongue may be removed from the slot at the forward end of the carton and inserted in the slot between the adjacent top and bottom sections at the rear of the carton. The cover will then be folded in the position shown in Figs. 1 and 2 and the forward face of the carton which preferably will be supplied with suitable advertising matter, will then be visible to any person in the vicinity of the position of the carton. The same advertising matter is visible whether the carton is in closed or display position inasmuch as it is the lower half section of the cover which is exposed when the cover is folded in the manner indicated.

The device just described is particularly suitable for light articles of merchandise and from its mode of formation, it has the advantage of internal bracing along its side edges which makes the entire carton of a greater rigidity than it would have with an equivalent amount of material differently disposed. The angular positioning of the side extensions also serves to provide an effective brace for the end of the carton to which the cover is hinged and serves to hold the folded cover in firm relationship with the base of the carton when said cover is in folded display position.

Other modes of applying the principle of our invention may be employed instead of the one explained, change being made as regards the structure herein disclosed, provided the means stated by any of the following claims or the equivalent of such stated means be employed.

We therefore particularly point out and distinctly claim as our invention:—

1. In an article of the character described, the combination of the base section of a carton having a cover hinged at an upper edge and therewith carrying display matter upon its upper side, a fold along an approximately intermediate transverse line of said cover and a second fold along a line parallel to and spaced a short distance from the line of the hinge of said cover, whereby to form a rear-

ward support extending from the hinge at the upper edge when the cover is opened, and a tongue formed at the front edge of said cover adapted to be tucked in at the front of the carton for closing or to be tucked in at the rear for display position. 70

2. In an article of the character described, the combination of the base section of a carton, a top section therefor adapted to hold said base section in assembled relation with the other parts of said carton, a cover formed on said top section provided with a plurality of transverse folds, a tongue at the front edge of said cover, and a pair of lateral extensions formed on said top section, folds provided in said extensions adjacent the upper edge of said carton, additional folds parallel to said last-named folds and spaced from the free edges of said extensions to permit said edges to be turned back against the bottom of said carton to space the extensions in angular relation to the side portions of the carton. 75 80 85

3. In an article of the character described, the combination of a base section of a carton of rectangular form having integral extensions turned upwardly to form side members, a top section for said carton comprising an open rectangular body section adapted to fit over the side members of said base section, a pair of lateral extensions continuous with the sides of said body section and an elongated cover portion continuous with one of the ends of said body section and hinged at the upper edge, said extensions adapted to be folded along a plurality of spaced longitudinal lines so as to occupy an angular position within the body of said carton and said cover being adapted to be folded along a plurality of transverse lines so as to have its forward edge inserted as a tongue between the front 95 100 105 of the base section and the top section when said cover is in closed position and between said parts at the rear of the box when said cover is folded upon itself so as to be held in display position, one of such folds causing the portion adjacent the hinge to project backwardly from such upper edge when the cover is in display position. 110

4. In an article of the character described, the combination of a base with four upstanding sides, and an open band adapted to fit about said upstanding sides and having extensions at the upper edges at opposite sides adapted to be folded within the base and having further folds to lie backwardly on the base to cause the extensions to occupy an inclined position along the sides thereof, each of said extensions being provided with a plurality of apertures cut in said angular portion of said extensions to receive the ends of various articles of merchandise adapted to be placed within said carton. 115 120 125

5. In an article of the character described, the combination of a base section of a carton comprising the bottom and four upstanding 130

side members, a top section in the form of an open band adapted to fit about said upstanding side sections, and a plurality of extensions continuous with the upper edge of said band, two of said extensions being provided with parallel longitudinal folds to turn backwardly on the base to cause inclined portions to be disposed within the side portions of said carton, said inclined portions having a plurality of apertures to receive the ends of articles of merchandise, and another of said extensions having a plurality of transverse

15 folds including a hinge-line fold and another fold spaced therefrom to permit the same to serve as a cover for said carton when in closed position or as a display device when in open position whereby the portion of the cover adjacent the base projects back from the upper edge of said base.

Signed by us, this 4th day of September, 20
1924.

JAMES E. FERGUSON.
